CATALYTIC CONVERSION OF HYDROCARBON OILS WITH THE USE OF DIFFERENT TYPES OF FEED OILS

Edwin M. Payton and James W. Slover, Phillips, Tex., assignors to Phillips Petroleum Company, a corporation of Delaware

Filed Nov. 18, 1959, Ser. No. 853,816

3 Claims. (Cl. 208—113)

This invention relates to catalytic conversion of hydrocarbon oils. In one of its aspects, the invention relates to a catalytic conversion of a plurality of hydrocarbon oils by adding these serially at spaced points along the axis of a riser to a catalytic reaction zone, the first oil added to and, therefore, admixed with the fresh or just regenerated catalyst being the most refractory oil and the last-added oil being the least refractory oil. In another of its aspects, the invention relates to a catalytic conversion operation wherein added to the riser of a fluid catalytic conversion reactor are the following oils in the order named: a raffinate from a solvent extraction zone in which a cycle oil obtained from a catalytic cracking zone is solvent extracted, a heavy virgin gas oil obtained from a vacuum flashing operation, and a topped crude from a crude oil fractionation system. At least a portion, if, indeed, not all of the vacuum gas oil can be replaced with virgin gas oil from the crude oil fractionation system.

In a prior art operation employing a fluid catalytic cracking reactor, raffinate obtained from heavy cycle oil solvent extraction was charged to the catalytic operation together with the virgin gas oil. It was found that the raffinate recycle (unconverted raffinate) built up in the system, causing backing out of some of the fresh gas oil charge, cutting down on production capacity of the unit.

We have conceived that the catalytic conversion, in the overall, of a crude oil from which gases, gasolines, and distillates boiling below gas oil have been removed, can be accomplished with increased efficiency by adding the raffinate from the cycle oil solvent extraction zone of such a system to the riser of the fluid catalytic conversion reactor, and therein causing cracking to a real extent of the raffinate and conditioning of the catalyst, following which virgin gas oil, which can include vacuum gas oil, is added to the mixture of catalyst and raffinate and conversion products of the cracking of the raffinate, thus producing a whole admixture of cracked products of both the raffinate and the gas oil, containing a catalyst, of such a nature that the mixture can be used for cracking of the topped crude resulting upon the removal of the gases, gasoline, distillates boiling lower than gas oil, and the gas oil from crude oil. Thus, in a unitary operation, we can use a single catalyst and a single cracking reaction zone, without loss of throughput, to convert the ordinarily crackable elements of a crude oil.

It is an object of this invention to provide a process for the catalytic conversion of hydrocarbon oils. It is a further object of this invention to provide a unitary combination of steps permitting the cracking of all of the components of a crude oil boiling higher than the gasolines and like distillates in a single reaction zone employ-

2

ing a single catalyst. A further object still of the invention is that of providing an operation in which raffinate recycle from a heavy cycle oil solvent extraction operation, in a catalytic conversion of cycle oils will not build up.

5 A still further object of the invention is to provide a series of steps in combination in a catalytic cracking operation in which there is employed a single catalyst and a single reaction zone permitting the conditioning of fresh or just regenerated catalyst so that it can be used to crack various 10 available streams, each of them at optimum conditions.

According to the present invention, there is provided a process for the conversion of a recycle raffinate obtained from solvent extraction of a cycle oil, in turn obtained in a fluid catalytic cracking conversion zone, a gas oil, and 15 a topped crude, which comprises in the order recited, adding said stream serially along the axis of a riser to a fluid catalytic conversion zone at points spaced so that the catalyst and resulting conversion products obtained addition of the raffinate to the riser will be a proper medium 20 in which to advantageously and most effectively to introduce gas oil, following which the then resulting mixture of cracked products and catalyst will be a proper medium into which topped crude from the distillation of crude oil can be received and cracked, with minimum carbon deposition and maximum gasoline yield.

Referring now to the drawing, 1 and 2 designate a conventional catalyst regenerator and reactor for conversion of hydrocarbons in the presence of the catalyst, respectively. 3 is a fractionation zone in which cracked prod-

30 ucts are fractionated into the usual light hydrocarbons 4, gasolines 5, light and heavy cycle oils 6 and 7, respectively, obtaining as a bottoms from the fractionation zone, a slurry of oil and catalyst unavoidably entrained from reac-

35 tor 2. This slurry is removed by pipe 8 to settler 9 for treatment, as later described. 10 is a crude oil fractionation zone in which crude oil charge is fractionated into the usual light hydrocarbon gases, gasolines and naphtha or kerosene distillates 11, 12 and 13, respectively, and into a virgin gas oil 14 yielding topped crude bottoms

40 15 which can be used as later described and/or, at least in part, sent to a vacuum flashing to produce asphalt and a vacuum gas oil. The light and heavy cycle oils 6 and 7 are each of them, at least in part, passed by way of pipes 17 and 18, together with oil from settler 9 by way of pipe

45 19 to solvent extraction zone 20 by way of pipe 21. In the solvent extraction zone, there is produced a paraffinic raffinate taken off by way of pipe 22. At the foot of the drawing in pipes 23, 24 and 25, there are fed, by way of riser 26, rising to reactor 2, raffinate from pipe 22, essen-

50 tially a paraffinic gas oil, virgin gas oil by way of pipe 24, and topped crude by way of pipe 25. In operation, earlier-used catalyst which has been regenerated in regenerator 1 and/or fresh catalyst is passed by way of pipe 27, into riser 26. Steam is supplied by way of pipe

55 28 to riser 26 and this steam is mixed with a paraffinic raffinate and then contacted as a steam-paraffinic raffinate admixture with the catalyst entering riser 26. Here, all of the paraffinic raffinate and steam which have been ad- 60 mixed contact all of the catalyst forming a paraffinic raf-

finate-steam-catalyst admixture in which cracking imme- diately ensues and is allowed to occur for a period of time sufficient to condition the entire mass with respect to cat-

alyst activity, temperature, and catalyst dilution with oil and catalyst and oil dilution with steam to create the conditions required to receive and to properly undertake the cracking of the virgin gas oil supplied by pipe 24 to riser 26. Here, again, all of the virgin gas oil contacts all of the preconditioned admixture of steam, partly converted paraffinic raffinate, and diluted and partly used catalyst. In similar fashion, the final admixture and preconditioned catalyst which are now suitable for undertaking optimum cracking of topped crude are admixed at the juncture of pipes 25 and 26 with topped crude entering riser 26 from pipe 25. It will be understood by those skilled in the art in possession of this disclosure and having studied the same that the diameter of riser 26 is effective to contain and to flow, along principles of fluid flow, large quantities of finely divided conversion catalyst and that this pipe can have, at any point, a diameter designed to contain a sufficient amount of preconditioned mixture for a sufficient amount of time, usually of the order of tenths of one second, to enable, prior to the entry of each succeeding oil stream, the conditioning of the catalyst, steam, already partly cracked oil and its diluted condition to provide optimum cracking conditions for the newly introduced oil. Also, as will be understood by those skilled in the art, cracking continues in riser 26 and is completed in reactor 2, from which products are taken overhead by way of pipe 29 to fractionation zone 3 for fractionation as earlier described.

Provision is made according to the invention to pass bottoms from settler 9, 30, 31 and 32 into pipes 23, 24 and 25, respectively, and this provides a trim adjustment of the overall catalytic activity of the catalyst oil and steam admixture in pipe 26. This feature of the invention importantly assists in the building of catalyst activity to control the reaction at points along riser 26, at which pipes 23, 24 and 25 communicate therewith.

The oil recovered from settler 9 is, in essence, a heavy gas oil or cycle oil and this oil is passed to the solvent extraction zone with the other cycle oils of the system. From this solvent extraction zone, in which a solvent such as sulfur dioxide is usually employed, there is removed by way of pipe 33, an aromatic gas oil preeminently suited for the production of carbon black by the so-called furnace method. Further, according to the invention, vacuum gas oil, which is a heavy virgin gas oil and which contains the metal contaminants of the crude oil to a large extent, is returned to the system from the vacuum distillation by way of pipe 34 and passed by way of pipe 24 to riser 26. It will be noted that the catalyst, upon reaching the juncture of pipes 24 and 26, has been preconditioned by cracking therewith the paraffinic raffinate and that, therefore, metal contaminants do not deposit on the catalyst but rather onto a layer of coke which has already formed on the catalyst particles. Likewise, the topped crude is added to the catalyst mass after it has been conditioned and, therefore, metal contaminants will be burned from the regenerator and be removed by way of the flue gas pipe 36 during regeneration in regenerator 1 of the catalyst in which, of course, the carbon deposit, the outer layers of which contain the metal contaminant, is gradually burned from the catalyst particles.

Heaters 40, 41 and 42 are provided to adjust the temperature of the oil streams 23, 24 and 25 just before these streams enter into riser 26.

We are aware of the disclosure of Serial Number 586, 812 filed May 23, 1956, now U.S. Patent No. 2,938,856, by George R. Hettick, and Patent 2,893,943, B. Vignovich, July 7, 1959, in which there are set forth, described and claimed fluid catalytic cracking operations which, although they resemble in some of their aspects, some of the aspects of the instant invention, are clearly distinguishable therefrom.

^a Range of 15,000 to 30,000 #/hr.

^b Based on charge oil.

^c 1085° F. is outlet temperature of zone 50.

^d Range of 0-10,000 #/hr. to vary residence time in this section to optimize conversion.

^e Based on 20,000 #/hr. steam for catalyst hydration. Part of the steam (28) entering zone (50) is absorbed by the catalyst. 25,000 #/hr. 20,000 #/hr. leaves 5,000 #/hr. for zone (51). Zone (51) has, therefore, this 5,000 #/hr. plus 5,000 #/hr. via (28a), and this 10,000 #/hr. steam +1240 bbls./hr. fresh feed to zone (51) gives the 8.1 #/steam/bbl. hydrocarbon.

^f 935° F. is outlet temperature of zone (51).

^g Range of 0-10,000 #/hr. as in (4).

^h 100 b./h. via (32) and 160 b./h. via (15).

ⁱ Based on 10,000 #/hr. steam from zones (50) and (51) together plus 5,000 #/hr. steam via (28b), and this 15,000 #/hr. steam +260 bbls./hr. fresh feed to zone (52) gives the 57.5 #/steam/bbl. hydrocarbon.

^j 905° F. is the outlet temperature of zone (52).

^k May operate without bed level.

^l Disregarding contact time in dilute phase.

45 In the above specific example, we have added, for simplicity, the slurry stream 32 to only the topped crude 15, which further decreases the activity of the catalyst in zone 52. This flow affords further control on the cracking of the least refractory topped crude.

It is seen that the catalyst activity decreases in the direction of flow of line 26 to the reactor 2. The slurry stream 32 which comprises spent catalyst and decant oil (which may or may not be very refractive) may be used 55 at the selected loci 50, 51, and/or 52 to adjust the activity of the catalyst, and to adjust the refractorinesses of the oils at these loci for optimum conversion of the different oils.

Further, additional control of conversion in zones 50, 60 51 and/or 52 is made by adjustment of the oil outlet temperatures from heaters 40, 41 and/or 42. In addition, steam addition via 28, 28a and/or 28b is also used for control of conversion in the reaction zones. That is, for a fixed charge rate, injection steam rates and slurry 65 recycle are chosen for optimum conversion of each of the feedstock.

The changing of the quantity of injection steam to a zone changes the residence time in that zone, which affects conversion. The residence time can also be controlled or 70 varied by using several injection points in each zone for each feedstock. Also, our invention is applicable to more than three feedstocks.

It is pointed out that required contact time for some least refractory materials may be so short that it may be 75 necessary to inject these materials directly into the re-

actor 2 bed instead of the riser as shown in our figure. The most refractory stock (most difficult to crack) is cracked with the most active catalyst, the highest reaction temperature, and the largest catalyst to oil weight ratio. (Residence time is adjusted by injection steam and feed nozzle location in the system.)

When, conventionally, the most refractory oil was catalytically cracked in the presence of the medium refractory oil, the most refractory oil was converted only about 30 percent, and the medium refractory oil was converted about 57 percent. By our invention, the most refractory oil is converted 55 percent and the medium refractory oil is converted 50 percent. Hence, our method of operation minimizes the buildup of recycle of unconverted most refractory oil which buildup is faced in the prior art, and our invention, therefore, does not have to back out the fresh feed or medium refractory oil as must be done in the conventional operation which thus loses production capacity in the conventional system.

Reasonable variation and modification are possible within the scope of the foregoing disclosure, the drawing, and the appended claims to the invention, the essence of which is that there have been provided a fluid catalytic cracking or conversion operation in which hydrocarbon oils of different types can be converted according to their crackability or refractoriness, as evident from the foregoing disclosure, and the drawing, and the appended claims, in the presence of a fluid catalyst, for example, a silica-alumina cracking catalyst, which, according to the invention, is preconditioned, as apparent herein, by first treating it by using it in the presence of steam to initiate cracking of a most refractory stock which can be a paraffinic raffinate resulting from the solvent extraction of a cycle oil in the system, followed by addition of virgin gas oil and/or vacuum gas oil, in turn followed by addition of topped crude oil to the fluid catalyst; and a method for additionally regulating the activity of the catalyst as it rises toward the fluid catalytic cracking reactor by providing for the introduction of catalyst slurry for its activity and/or diluted effect, together with any one or more of the streams of oil which are added to the catalyst.

We claim:

1. In a fluid catalytic cracking operation in which a

fluid catalyst mass of particles is employed and in which there are cracked in the presence of the catalyst a refractory paraffinic oil obtained by solvent extraction of a cycle oil formed in the system, a virgin gas oil obtained from a crude oil by fractionation of the same, and a topped crude obtained from said crude oil by fractionation of the same, the steps which comprise admixing steam and catalyst and then adding successively to the mixture of steam and catalyst the oil streams in the order mentioned under cracking conditions.

2. A process according to claim 1 wherein there is obtained upon the fractionation of products from the catalytic cracking reaction, a catalyst slurry, and wherein this slurry is added to at least one of said oil streams to assist in controlling the total catalyst activity or the dilution in the combined stream of catalyst as it moves toward the catalytic cracking reaction zone.

3. In a fluid catalytic cracking operation in which a fluid catalyst mass of particles is employed and in which there are cracked in the presence of the catalyst a refractory paraffinic oil obtained in the system, a virgin gas oil obtained from a crude oil by fractionation of the same, and a topped crude obtained from said crude oil by fractionation of the same, the steps which comprise admixing steam and catalyst, then adding successively to the mixture of steam and catalyst the oil streams in the order mentioned, then continuing the conversion of the combined catalyst and oil streams, obtaining a cracked product stream, separating from said cracked product stream a cycle oil, recovering from said cycle oil by solvent extraction a refractory paraffinic oil and using the last-mentioned oil as said refractory paraffinic oil obtained in the system.
